BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Original application filed January 16, 1924, Serial No. 686,564. Divided and this application filed June 18, 1925. Serial No. 37,951.

This application is a division of a copending application of B. M. Shipley, Serial No. 686,564, filed January 16, 1924.

One object of this invention is to provide a novel "cashier's key", which will not only set up type wheels to print the cashier's number, but will also control locking mechanism, so that the machine cannot be released for operation, unless the cashier's key is in position in the machine.

Another object of the invention is to permit the manual release of any depressed keys which have been depressed through error, whether the cashier key is in position in the machine or not.

With these and incidental objects in view, the invention consists of certain novel features of construction, and combinations of parts, the essential elements of which are set forth in appended claims, and a preferred form of embodiment of which is hereinafter described, with reference to the drawings which accompany and form part of this specification.

25 Of said drawings,

Fig. 1 is a side elevation of the right hand end of the machine, in which the present invention is embodied.

Fig. 2 is a detailed sectional view taken 30 on the line 2—2 of Fig. 3.

Fig. 3 is a detail top plan view of the cashier's key in its proper position in the machine.

Fig. 4 is a detail view of one of the release 35 keys of the machine, and shows the detent for locking the keys in their depressed positions, and also the mechanism for releasing them.

Fig. 5 is a detail side elevation of a portion 40 of the release mechanism used in the present machine, together with the detent, and one of the keys of the release bank, which cooperates therewith.

Fig. 6 is a detail view of the link used to 45 restore the release shaft at the end of an operation, and the spring which rocks the release shaft when released.

Fig. 7 is a detail side elevation of the mechanism operated by the cashier's key to oper-

ate the type setting racks to position a type wheel appropriate to said key.

Fig. 8 is a detail view of the ends of the racks shown in Fig. 7, and the means whereby the movement given to the racks by the cashier's key will be transmitted to its appropriate type wheel.

Described in general terms, this invention includes a detachable "cashier's key", which may be inserted in the machine or removed therefrom at will. One function of the cashier's key is to absolutely lock the machine against operation when the key has been removed therefrom. A second function is to automatically set up type carriers in the printer of the machine to which it is applied, said printer being shown in the above-mentioned parent application. Still another function of the device is to permit the manual release of any of the keys of the machine, which may have been depressed by mistake, even though the cashier's key has been removed from the machine.

Release shaft

This machine is provided with a shaft 30 (Figs. 1, 4, 5 and 6) which is known herein and in the application above referred to, as the release shaft. It has been given this name due to the fact that it must be rocked 35 in a clockwise direction, as viewed in all of these figures, before the machine can be operated. The shaft 30 normally tends to rock in a clockwise direction (Fig. 6), by reason of the following mechanism:

Fast on the shaft is an arm 31, which at its left hand end carries a stud 32, upon which is pivotally mounted a pair of guides 33 having teats projecting into and acting as guides for a compression spring 35. At 40 its lower end the spring 35 surrounds a teat 36, which extends upwardly from the base of a slot 37 in a link 38. It can be seen from the above that through the spring 35 and arm 31, the shaft 30 normally tends to 45 rock in a clockwise direction.

The clockwise movement of the shaft 30 is normally prevented by means of the following mechanism:

Fast on the shaft 30 is an arm 39 (Fig. 100

5), which carries a half-round stud 40, cooperating with a pawl 41, loosely mounted on a shaft 42, supported by the machine side frames.

5 The machine is provided with a plurality of banks of depressible keys, one of which is known as the release bank. Fig. 5 shows the uppermost key only, in this bank, and the means whereby the depression of any 10 of the keys in this bank will release the machine. The key 45 is slidably mounted in a frame (not shown) and has a laterally projecting pin 46, which is adapted to cooperate with an inclined edge 47, of a detent 48, supported at its upper end by an arm 49, and at its lower end by a similar arm not shown.

The arm 49 which supports the upper end of the detent 48, has a projecting arm from which extends a pin 50. This pin normally 20 lies just in the rear of an upwardly projecting lever 51, which is loose on the shaft 42. The lever 51 normally tends to rock clockwise, due to a spring 53 attached thereto, and thereby through its contact with the pin 25 50, holds the detent 48 in its normal upper position. The lever 51 carries a pin 54, which extends through a bifurcated arm 55, which is in turn connected to the release pawl 41 by means of a yoke 56.

30 It can be seen from the above description that when one of the release keys 45 is depressed, the detent 48 is moved downwardly, and thereby the arm 49 is moved clockwise about its support. This will cause the pin 35 50 to rock the lever 51, bifurcated arm 55, and release pawl 41, counter-clockwise a sufficient distance to move the end of the release pawl 41 away from the half-round stud 40, carried by arm 39, thereby permitting 40 the spring 35 to rock the shaft 30 in a clockwise direction. The clockwise movement of the shaft 30 closes a motor switch (not shown), when a motor is provided, and causes the machine to be operated.

45 *Cashier's key*

A cashier's key is provided in the present invention to positively lock the machine when the said key is removed from an appropriate slot which is provided therefor. The cashier's key 65 is shown in Figs. 3 and 50 7. The means whereby the removal of the cashier's key will lock the register, will now be described.

55 Fast on the right hand end of the release shaft 30 is a lever 66 (Fig. 1), to which is pivoted the upper end of a link 67. At its lower end the link 67 has a long slot 68 formed therein, which cooperates with a 60 pin 69, carried by an arm 70, fast on a shaft 71, which is supported by a bracket 72, secured to the printer frame 73. The shaft 71 in this instance has three holes therein, in which are mounted three spring plungers or 65 tumblers 74. The bracket 72 also has holes

therein in alignment with the holes in the shaft 71, and in these holes in the bracket there are also spring plungers 75 (Figs. 2 and 3). The bracket 72 has a key-way 76, in which the shank 77 of the cashier's key 65 is adapted to slide. Fig. 2 shows the cashier's key in position in the machine. The side of the shank 77 of the cashier's key has notches formed therein, which cooperate with the ends of the plungers 75, and which through these plungers 75 will position the tumblers 74, so that their left hand ends (Fig. 2.) will be flush with the periphery of the shaft 71.

When the tumblers 74 are held in these 80 positions, it is evident that the shaft 71 can be rotated, and therefore when the release shaft 30 is free to rotate clockwise by the depression of one of the release keys, this movement of the shaft 30 will be permitted. Whenever, however, the cashier's key is removed from the machine, the springs which 85 cooperate with the tumblers 74, will force these plungers to the left, as viewed in Fig. 2, a sufficient distance to cause them to slightly enter the openings in the bracket 72, and in this manner completely lock the shaft 71 against movement. With the tumblers 74 in these positions, even though the release shaft 30 is free to rock clockwise by the depression 90 of one of the keys in the release bank, this rocking movement of the shaft 30 is prevented. When the cashier's key is again inserted in the machine, the notches in the edge thereof will cooperate with the plungers 95 75, which will in turn move the tumblers 74 flush with the periphery of the shaft 71, so that this shaft can be rocked, and thereby permit the release shaft 30 to be rocked to release the machine.

Means for setting up type carriers by the cashier's key

In order to print the cashier's number on the printing medium used in the machine, when one of the cashier's keys is inserted in the proper opening in the machine, means is provided for setting up appropriate type carriers. In order to accomplish this purpose the shank of the cashier's key carries a 110 plurality of upwardly extending pins or wards 85, (Figs. 2, 3 and 7) which are adapted to cooperate with downwardly extending noses 86, of slidable bars 87, supported on suitable studs 88, projecting from the printer frame. These bars are normally held in their extreme right hand positions (Figs. 3 and 7) and are returned to their normal positions upon the removal of the cashier's key, by means of springs 89, which extend between pins on the bars, and suitable pins 115 projecting from the printer frame.

At their left hand ends the bars 87 have upwardly extending noses 90, which have 120 teeth 105 cooperating with similar teeth 125

formed in the lower edges of laterally extending racks 91, supported at their right hand ends on a stud 92 (Fig. 7), and at their left hand ends on a stud 93 (Fig. 8). At their left hand ends the racks 91 have teeth 94 formed thereon, which mesh with pinions 95, supported on a shaft 96 or sleeves 97, carried by said shaft. On the forward end of the shaft 96 and the sleeves 97 are partial gears 98, which mesh with pinions 99, loosely mounted on a shaft 100, and which in turn mesh with pinions or type wheels 101 and 102, supported by shafts 103 and 104, projecting from the printer frame. When one of the cashier's keys 45 is inserted in the keyway 76 and pushed in to its innermost position, the pins or wards 85 will come into contact with the downwardly extending noses 86 of the bars 87, and move the bars differentially toward the left, in accordance with the position of the pins on the shank of the inserted cashier's key. The movement of the bars 87 toward the left will through the upwardly extending noses 90 thereof, move the racks 91 also toward the left differentially, and thereby through the pinions 95, sleeves 97 or shaft 96, and partial gears 98, operate the pinions 99 and the type wheels 101 and 102 differentially to set up the cashier's number thereon.

Manual key release

Mechanism is provided for rocking the release shaft 30 in a counter-clockwise direction (Figs. 1 and 4), in case the operator depresses the wrong keys in entering a transaction and wishes to return all the keys to their normal undepressed positions.

It will first be described how the transaction keys are locked in their depressed positions. Each of the keys 45 (Fig. 4) carries a laterally projecting pin 110, which is adapted to cooperate with a beveled nose 111, projecting upwardly from a detent 112. The detent 112 is pivotally connected at its upper end to an arm 113, which is in turn pivotally mounted on the key frame in the manner shown in the parent application previously mentioned.

The detent 112 due to the influence of a spring, not shown herein normally tends to move towards the right (Fig. 4), and thereby rock the arm 113 in a counter-clockwise direction. When a key is depressed a pin 110 through the nose 111 rocks the detent downwardly or towards the left (Fig. 4) until such a time as the pin passes the lower end of the nose, whereupon the detent will move upwardly under the influence of a spring as above mentioned, and the shoulder 114 of the nose 111 will engage the pin 110 and hold the key in its depressed position.

When the machine is released, an arm 115 (Fig. 4) which is secured to the release shaft 30, is rocked with the shaft in a clockwise

direction. This movement of the arm 115 will position an arm 116 rigid therewith, in engagement with the upper edge of an arm 117, loosely mounted on the shaft 118. This arm 117 has a notch 119, which cooperates with a pin 120 carried by an arm 121 rigid with the arm 113. It can, therefore, be seen that after the machine has been released, it is impossible to move the detent 112, and therefore no keys in this bank can be pressed. When, however, a key 45 has been partially depressed, the arm 117 will be positioned in the path of the arm 116, and, therefore, it will be impossible to release the machine. Upon the complete depression, however, of one of the keys 45, the arm 117 again moves clockwise out of the path of the arm 116, and the machine can thereupon be released.

In order to release the depressed keys at the end of an operation, the shaft 30 is rotated counter-clockwise, slightly past its normal position, in which it is shown in Fig. 4. This will cause the end 122 of the arm 115, to contact a beveled edge of the arm 121 of arm 113, thereby rocking the arm 113 clockwise about its pivot, and moving the detent 112 downwardly a sufficient distance to free the pin 110 from the shoulder 114, whereupon a spring (not shown) which surrounds the shank of the key will raise the key to its undepressed position.

The means for releasing the depressed keys manually will now be described. Attached to the lever 66 (Fig. 1) is a link 130, which carries a roller 131. Pivoted to the side frame of the machine is a lever 132, which has a projection 133, adapted to cooperate with the roller 131. The lever 132 is also provided with a handle 134 and when it is desired to release the keys, the lever 132 is rocked counter-clockwise. Upon this movement of the lever 132, the projection 133 thereof will contact with the roller 131 on link 130, and raise this link, which movement through the lever 66 will rock the release shaft 30 in a counter-clockwise direction. This movement of the shaft, as has already been described, will release the depressed keys.

When the machine has been released, the release shaft has been moved in a clockwise direction. This will lower the link 130 sufficiently to position a lug 136 carried thereby, in front of an arm 137 of the lever 132. It is evident that this will make it impossible to rock the lever 132 in a counter-clockwise direction for the purpose of releasing the depressed keys.

When the shaft 30 is rocked counter-clockwise by the key release lever 132, to release the depressed keys, the link 67 is moved downwardly. If the cashier's key should happen to be out of the machine, the shaft 71 would be locked against movement. For this reason a flexible connection must be provided between the link 67 and arm 70. The lower

end of the link 67 has the long slot 68 formed therein, through the lower end of which the pin 69 extends. A plunger 140 lies in the slot 68, with its lower end butting against the pin 69. The plunger is held in position in the slot by two plates 141, riveted to its sides, and extending over the sides of slot 68. At its upper end the plunger 140 has a pin 142, which extends upwardly in the slot and supports a coil spring 143. At its upper end the spring is seated on a pin 144, which projects downwardly from the link in the upper end of the slot 68. It can be seen from the above description that when the link 67 is lowered with the cashier's key out of the machine, the spring 143 will be compressed sufficiently to compensate for said downward movement, and the arm 70 and shaft 71 will not be strained.

20 The link 130 has a slot 145 cut therein, through which projects a key barrel 146. If it is desired to lock the machine against operation, the lever 132 is rocked so as to raise the link 130. A key is then inserted in the key barrel 146, and given a one-half rotation. A portion of the key barrel 146, which cooperates with the slot 145 is eccentric so that upon the rotation of the key and the barrel, the link 130 will be rocked slightly counterclockwise about its pivot, and then when the handle 134 is released and the link 130 is permitted to move downwardly, a notch 147 on the extreme lower end of the link 130 will engage a lug 148, which projects from the side frame. It can be seen, therefore, that so long as the link 130 rests upon the lug 148, it will be impossible to lower this link, to permit the rocking of the release shaft 30, and therefore the machine cannot be released for operation.

45 A shutter 150 is attached to the lower end of the lever 132, in such a position that it normally covers the opening in the key barrel 146. When the lever 132 is rocked counterclockwise, however, to its extreme position, the shutter 150 will be moved away from in front of the key barrel 146, so that the key can be inserted to lock the machine. A spring 151 is provided, stretched between a pin on the frame and a pin on the lever 132, to restore this lever to its normal position, when it is released by the operator.

55 While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope 60 of the claims which follow.

What is claimed is:

65 1. In a machine of the class described, a release shaft, a lock shaft, and a flexible connection between said shafts for rendering the lock shaft effective to prevent a machine re-

lease movement of said release shaft while permitting movement thereof in an opposite direction.

2. In a machine of the class described, a release shaft, a lockable member normally locked in home position, a key for releasing said member, a connection between said shaft and member to prevent a machine release movement of said shaft, and a spring involved in said connection for moving said member to home position, as the release shaft is moved to home position.

3. In a cash register, the combination of a release shaft, an arm fast on said shaft, a link pivoted on said arm, spring means for rocking said shaft and arm and lowering said link, a slot in said link, and an eccentric cooperating with said slot.

4. In a cash register, the combination of a release shaft, an arm fast on said shaft, a link pivoted to said arm, spring means for rocking said shaft and arm and lowering said link, a slot in said link, a lug normally out of the path of movement of said link, and an eccentric cooperating with said slot for moving said link into cooperative relation with said lug.

5. In a cash register, the combination of a release shaft, an arm fast on said shaft, a link pivoted to said arm, spring means for rocking said shaft and arm and lowering said link, a slot in said link, an eccentric cooperating with said slot, a lug normally out of the path of movement of said link, and means for turning said eccentric to move said link sufficiently so that upon its downward movement it will engage said lug and prevent the rocking of said shaft.

6. In a cash register, the combination of a shaft, means for rocking said shaft to release the machine, a link adapted to be lowered upon the releasing movement of said shaft, a stud normally out of the path of movement of said link, means for raising said link, and means for rocking said link about its pivot far enough to bring said link and stud into cooperative relation to prevent a rocking movement of said shaft.

7. In a cash register, the combination of a shaft, means for rocking said shaft to release the machine, a link adapted to be lowered upon the releasing movement of said shaft, a stud normally out of the path of movement of said link, means for raising said link, means for rocking said link about its pivot far enough to be intercepted by said stud, thereby preventing said releasing movement, and means for preventing the rocking of said link until said raising movement is completed.

8. In a machine of the class described, the combination of a shaft, means for rocking said shaft to release the machine, a link adapted to be lowered upon the releasing movement of said shaft, a stud normally out

of the path of movement of said link, a manually operated lever for raising said link, an eccentrically mounted key barrel projecting through a slot in said link and adapted, when rotated, to rock said link about its pivot far enough to bring said link into cooperative relation with said stud to prevent said releasing movement, and a plate carried by said lever adapted to cover the key hole of said key barrel until said link is raised to its greatest extent.

9. In a machine of the class described, the combination of a shaft, means for rocking said shaft to release the machine, a link adapted to be lowered upon the releasing movement of said shaft, a stud normally out of the path of movement of said link, a manually operated lever for raising said link, an eccentrically mounted key barrel projecting through a slot in said link and adapted, when rotated, to rock said link about its pivot far enough to bring said link into cooperative relation with said stud to prevent said releasing movement, and means for preventing the operation of said key barrel until said manually operated lever is rocked to its greatest extent.

10. In a machine of the class described, the combination of a shaft, means for rocking said shaft to release the machine, a link adapted to be lowered upon the releasing movement of said shaft, a stud normally out of the path of movement of said link, a manually operated lever for raising said link, means for obstructing the movement of the manually operated lever when the operation of the machine has commenced, an eccentrically mounted key barrel projecting through a slot in said link and adapted, when rotated, to rock said link about its pivot far enough to bring said link into cooperative relation with said stud to prevent said releasing movement, and also render the obstructing means ineffective.

11. In a cash register, the combination of a plurality of banks of depressible keys, means for holding said keys in their depressed positions, a release shaft common to all of said banks, an arm fast on said shaft, a link pivoted to said arm, a manually movable lever for raising said link in order to rock said arm and shaft, means carried by said shaft for releasing said depressed keys, and a lug on said link, and normally out of the path of the manually movable lever, which lug will obstruct the action of said manually movable lever when the operation of the machine has commenced.

12. In a machine of the class described, the combination of a depressible key, an oscillatory shaft adapted, when rocked in one direction, to release the machine for operation, and when rocked in the opposite direction, to release the depressed key, a member adapted to be locked in fixed position, and a link at-

tached to said shaft and said member and adapted normally to prevent movement of said shaft to release the machine while permitting movement of the shaft in the opposite direction to release the depressed key.

13. In a machine of the class described, the combination of a depressible key, an oscillatory shaft adapted, when rocked in one direction, to release the machine for operation, and when rocked in the opposite direction, to release the depressed key, a link attached to said shaft to prevent movement thereof in said one direction, and a spring connected to said link to permit movement of the shaft in the opposite direction.

14. In a machine of the class described, the combination of a depressible key, an oscillatory shaft adapted, when rocked in one direction, to release the machine for operation, and when rocked in the opposite direction, to release the depressed key, a link attached to said shaft and adapted normally to prevent movement thereof in one direction and permit movement of the shaft in the opposite direction, and an insertible member for disabling said link to permit movement of said shaft in said first-named direction.

15. In a machine of the class described, the combination of a depressible key, an oscillatory shaft adapted, when rocked in one direction, to release the machine for operation, and when rocked in the opposite direction, to release the depressed key, a link attached to said shaft and adapted normally to prevent movement thereof in one direction and permit movement of the shaft in the opposite direction, an insertible member to control the link to enable movement of said shaft in the direction to release the machine, and a plurality of spring plungers co-operating with said member to permit movement of said link in the last-named direction.

16. In a machine of the class described, the combination with a release shaft; and means to rock the shaft in one direction to release the machine for operation; of a link connected with the shaft and shiftable in one direction upon the rotation of the shaft to release the machine; an abutment normally out of the path of the link; manually operable means to shift the link in a direction opposite to that in which it is shifted by the shaft when the latter is rocked to release the machine; and a manually adjustable eccentric adapted when shifted to one of its positions to shift the link into cooperative relation with its abutment to prevent the release shaft from releasing the machine for operation.

17. In a machine of the class described, the combination with a release shaft; and means to rock the shaft in one direction to release the machine for operation; of a link connected with the shaft and shiftable in one direction upon the rotation of the shaft to release the machine; an abutment normally

out of the path of the link; manually operable means to shift the link in a direction opposite to that in which it is shifted by the shaft when the latter is rocked to release the machine; a manually adjustable eccentric 5 adapted when shifted to one of its positions to shift the link into cooperative relation with its abutment to prevent the release shaft from releasing the machine for operation; 10 a manipulative device removably insertible in the eccentric; and means controlled by the manually operable means to prevent insertion of the manipulative device save when the link is at one limit of its path of travel.

15 In testimony whereof I affix my signature.
BERNIS M. SHIPLEY.
